UNITED STATES PATENT OFFICE.

SAMUEL F. FIELD, OF FINDLAY, OHIO.

OIL-WELL PUMPING-RIG.

No. 797,421.

Specification of Letters Patent.

Patented Aug. 15, 1905.

Application filed September 21, 1904. Serial No. 225,387.

To all whom it may concern:

Be it known that I, SAMUEL F. FIELD, a citizen of the United States, residing at Findlay, in the county of Hancock and State of Ohio, have invented a new and useful Oil-Well Pumping-Rig, of which the following is a specification.

This invention relates to a pumping power, and more especially to rigs of that general class wherein a number of oil-pumps are connected to a single power-transmitting means.

The principal object of the invention is to provide a device of this class in which the apparatus is made for adjusting the connections to suit the locations of the pumps, the parts being so constructed as to permit of very many adjustments in accordance with the position of the pump, its stroke, the length of the connecting-rod, and the vertical height of the rod.

A further object of the invention is to provide a device of this character in which the adjustments may be accomplished both quickly and accurately without the exercise of any special mechanical skill.

With these and other objects in view, as will more fully hereinafter appear, the invention consists in certain novel features of construction and arrangement of parts hereinafter fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a plan view of a pumping power constructed in accordance with the invention. Fig. 2 is a transverse sectional elevation of the same on the line 2 2 of Fig. 1. Fig. 3 is a plan view of the base-plate. Fig. 4 is a detail perspective view of one of the adjustable wrist-pin-carrying blocks detached. Fig. 5 is a similar view of another form of wrist-pin-carrying block that may be employed.

Similar numerals of reference are employed to indicate corresponding parts throughout the several figures of the drawings.

The device forming the subject of the present invention is one of that general type employed in oil-regions for the simultaneous pumping of a number of wells which may be

located at irregular distances from each other and where the expense of separate pumping-engines and operating mechanism for each well would be prohibitive. This mechanism is designed as an intermediary between the engine or a similar source of power and the several pumps.

The base-plate 10 is provided on its under face with a number of projecting lugs or ribs 2, which serve to more firmly connect the bed-plate to its foundation or supporting timber. At the center of the bed-plate is a short vertical post 12, the outer surface of which is faced and affords a bearing for the crank-disk 13. This base is further supported by an annular flange 14, which engages with the periphery of the disk-hub. That portion of the surface of the bed-plate between the periphery of the post 12 and the inner wall of the flange 14 is provided with a number of drainage-openings 15, through which any water or accumulations of lubricating material may readily pass. The crank-disk is held from vertical movement by a cap-plate 16 and bolt 17, the plate being of a diameter sufficient to extend over the hub of the crank-disk. The crank-disk is provided with an annular row of openings 17, around each of which is grouped a series of bolt-receiving openings 18 and a series of lugs 19, all of the openings being of the same size and all being equidistantly spaced. From the edge of the crank-disk projects an ear or lug 21, to which is connected a rod 22, leading from an engine or other source of power, and from this engine the crank-disk receives oscillatory movement to be transmitted through one or more connecting-rods to the well-pumps or other points where the power is to be utilized.

In connection with the crank-disk there is employed any desirable number of wrist-pin-carrying blocks, and said blocks may be of the construction shown in Fig. 4 or that shown in Fig. 5. The block 25 shown in Fig. 4 has a substantially circular body portion, in the bottom of which are formed recesses 26 for the reception of lugs 19, and through said body portion extend bolt-holes 27, which may be in alignment with the bolt-openings 18 in the crank-disk, and when once adjusted bolts are passed through these openings and firmly secured in place. As all of the openings and all of the lugs are equidistantly spaced, the block may be placed at any point on the crank-disk, and it may be turned with any one of the openings 17 as a center and

adjusted to eight different positions with respect to each group of lugs 19. The block is provided with a projecting arm 28, carrying a number of wrist-pins 29, to any one of which may be connected the pump-operating rod, and by proper adjustment of the block connecting-rods of variable length may be employed and the power transmitted in any direction. In many cases the connecting-rods require wrist-pins disposed in a horizontal plane somewhat below that of the block 25, and in such cases blocks of the construction shown in Fig. 4 are employed. These blocks are provided with arms 28', the outer ends of which are in substantially the same plane as the upper surface of the crank-disk. The arm in this case is provided with a number of wrist-pins 29, to any one of which the rod or rods may be connected.

It is obvious that by employing the proper number of wrist-pin-carrying blocks the apparatus may be used for the transmission of power to a large number of pumps or employed for the transmission of power to apparatus of the same or different character. The connecting-rods may be led up to the crank-disk and the blocks attached to the disk in such manner as to properly accommodate the ends of the rods, and by further adjustment of the blocks the wrist-pins may be moved to a greater or less distance from the center of movement of the disk, and thus alter the extent of reciprocatory movement imparted to the rods.

Having thus described the invention, what is claimed is—

1. In an oil-well pumping-rig for the transmission of power from a central source to a plurality of pumps, a crank-disk mounted for oscillatory movement in a horizontal plane, and having an annular series of pin-receiving

openings, a set of lugs and a set of bolt-receiving openings grouped around each opening, a wrist-pin-carrying block having a rigid centrally-disposed pin adapted to enter one of the pin-receiving openings and forming an axis for circumferential adjustment of the block, said block being further provided with recesses for the reception of the lugs, and with a set of bolt-receiving openings grouped around the pin in the same relative order as the bolt-receiving openings of the disk are grouped around the pin-receiving openings thereof, whereby said block may be adjusted circumferentially around the disk and around its own pin, substantially as specified.

2. In an oil-well pumping-rig for the transmission of power from a central source to a plurality of pumps, a crank-disk having an annular series of pin-receiving openings, a set of lugs grouped around each opening, the lugs of each set being correspondingly disposed throughout the entire series of sets, said crank-disk being further provided with a plurality of equidistantly-spaced bolt-receiving openings grouped around each pin-receiving opening, a wrist-pin-carrying block having a central pin adapted to any one of the pin-receiving openings, and being provided with recesses for the reception of the lugs, said recesses being equidistantly spaced to permit circumferential adjustment of the block, and bolts for securing the block in adjusted position.

In testimony that I claim the foregoing as my own I have hereto affixed my signature in the presence of two witnesses.

his
SAMUEL F. + FIELD.
mark.
